SEED FLAT

Malcolm H. Kuhn, Doylestown, Pa., assignor to W. Atlee Burpee Company, Philadelphia, Pa., a corporation of Pennsylvania

Continuation of design applications Ser. No. 63,932, Feb. 13, 1961, Ser. No. 64,416, Mar. 21, 1961, and Ser. No. 64,417, Mar. 21, 1961. This application June 13, 1962, Ser. No. 70,685

Term of patent 14 years

(Cl. D35—3)

FIG. 1 is a top perspective view taken from one side and one end of a seed flat embodying my new design; FIG. 2 is an elevation view thereof taken from the side opposite to that shown in FIG. 1;

FIG. 3 is an elevational thereof taken from the end opposite to that shown in FIG. 1;

FIG. 4 is a top plane view thereof the bottom being substantially plain;

FIG. 5 is an enlarged fragmentary sectional view thereof taken on line 5-5 of FIG. 4;

FIG. 6 is a top perspective view taken from one side and one end thereof, the top being in a reversed position;

FIG. 7 is a top perspective view of a modified form of the seed flat shown in FIG. 1; and

FIG. 8 is an enlarged fragmentary sectional view thereof taken on line 8-8 of FIG. 7.

This application is a continuation of my co-pending

applications, Serial No. D. 63,932, filed Feb. 13, 1961, and Serial Nos. D. 64,416 and D. 64,417, both filed Mar. 21, 1961, all now abandoned.

I claim:

The ornamental design for a seed flat, as shown and described.
